SWITCH PLATE

Maxwell E. Holland, Fort Atkinson, Wis., assignor
to Thomas Industries, Inc., Fort Atkinson, Wis.,
a corporation of Delaware

Filed Jan. 26, 1959, Ser. No. 54,289

Term of patent 14 years

(Cl. D26—13)

FIG. 1

FIG. 2

FIG. 3

FIG. 4

FIG. 5

Fig. 1 is a front elevation of the switch plate showing my new design;

Fig. 2 is a side elevation view, the opposite side being substantially a mirror image;

Fig. 3 is a section view taken on the line 3—3;

Fig. 4 is a bottom plan view thereof; and

Fig. 5 is a perspective view thereof.

Diagonal lines of shading indicating transparency have been employed on the transparent surfaces in the drawing.

I claim:

The ornamental design for a switch plate, substantially as shown and described.
